United States Patent Office.

JOEL S. HOOD AND JOHN H. HOOD, OF WASHINGTON CITY, DISTRICT OF COLUMBIA.

Letters Patent No. 78,967, dated June 16, 1868; antedated June 6, 1868.

IMPROVEMENT IN PERPETUAL REGISTERS.

The Schedule referred to in these Letters Patent and making part of the same.

TO ALL WHOM IT MAY CONCERN:

Be it known that we, JOEL S. HOOD and JOHN H. HOOD, of Washington city, in the county of Washington, and District of Columbia, have invented a new and useful Improvement in Perpetual Registers; and we do hereby declare that the following is a full, clear, and exact description of the same, reference being had to the accompanying drawing, through letters of reference marked thereon, in which—

Figure 1 represents a face view of a register, showing our invention, and

Figure 2 a transverse section of the same, on an enlarged scale, taken on the line $z z$ of fig. 1.

The same letters of reference occurring on both figures indicate corresponding parts.

The object of our invention is to furnish a convenient and perpetual register, for showing the number of articles of each kind that may have been sent to the wash, the price of each article on a bill of fare, or for other like purposes; and it consists in a novel arrangement and combination of parts, whereby a very simple and cheap changeable register is produced.

To enable others to make and use our invention, we will describe its construction and operation, by referring to the drawing, in which—

A represents the face-plate or card, which is punched with a series of round or square holes, a , and slots b , said slots extending, one above another, down the centre of the plate, or thereabouts, in a horizontal direction, and parallel with each other, from near each of the holes a , nearly to the edge c of the plate or card A, and on the opposite side of the holes a said plate A is provided with strips, d , of suitable form to receive a tablet, C, on which is printed, or otherwise delineated, the list of articles, the number or price, &c., of which is intended to be registered.

Instead of the strips d , the plate A, when made of metal, might have a series of clips partially punched out of it, so as to bend over the edge of the tablet, and thus retain it on the plate A, or, when this plate is made of card-board, the list of articles might be printed upon it, or on a slip of paper pasted to it. The upper part of the plate A is punctured with two openings, e and i , the purpose of which will be explained hereinafter.

The back plate B may be punched with holes and slots, &c., precisely the same as the face-plate; the holes a and the apertures e and i , however, in it, are unnecessary. The two plates, A and B, are then placed together, in such a position that the slots b' in the back one come behind the tablet C, and in range with the slots b in the face-plate. Between these two plates is inserted a series of slides, m , which are provided at one end with a stud, s , passing rearwardly through the slots b' , by which means that end of the slide is supported; their other ends are provided with knobs n , the shanks of which, passing through the slots b in the face-plate, sustain the other end of the slides, and by which they may be slipped backward or forward, to bring any desired number or figure on the face of the slide in the centre of the hole a , in range with it and with the article on the tablet C to be registered against. These slides may have the figures engraved or otherwise marked on the face, or they may be constructed so as to attach a printed or marked card.

In the upper part, between the plates A and B, are inserted two disks, D, represented in the drawing in red lines, the one being marked radially with the names of the months, and the other with the days of the month; these are supported on pivots r passing through the plates A and B, in such position that their peripheries extend slightly beyond the edge of the plates, so that, by applying the finger thereto, they may be turned to bring the month and the day of the month so as to be seen through the apertures e and i , or they may be turned by a knob on the axle; thus the time is registered by adjusting the disks D, and the number of each article on the tablet, by moving the slide in range with it until the proper figure is brought in view through the hole a opposite to it, and if it is desired to show the total number of pieces thus recorded, we mark the figures on two or three of the slides at the lower end of the column, transversely to the length of the slide, and then add up the figures in the column, and register the units by the bottom slide, the tens by the one above in and the hundreds by the third from the bottom.

This article is intended to be hung in the housekeeper's room, or be tacked in the top of a travelling-trunk, for which latter purpose a slight modification in form or outline may be made.

Having thus described our invention, what we claim as new, and desire to secure by Letters Patent, is—

1. The slides m , constructed with rearwardly-projecting spurs s at one end, and knobs n on the front side of their opposite ends, arranged in combination with the slotted plates or cards A B for operation together, as shown, and for the purposes described.

2. The disks D, in combination with the slotted plates A B and slides m , all arranged substantially as and for the purpose specified.
